UNITED STATES PATENT OFFICE.

MORITZ SCHENKEL, OF CHARLOTTENBURG, GERMANY, ASSIGNOR TO SIEMENS-SCHUCKERTWERKE GESELLSCHAFT MIT BESCHRANKTER HAFTUNG, OF SIEMENSTADT, NEAR BERLIN, GERMANY, A GERMAN CORPORATION.

ELECTRIC INSTALLATION.

Application filed December 4, 1920. Serial No. 428,424.

To all whom it may concern:

Be it known that I, MORITZ SCHENKEL, a citizen of the German Empire, residing at Charlottenburg, Germany, have invented certain new and useful Improvements in Electric Installations (for which I have filed application for patent in the following countries: Germany, November 15, 1915, Ser. No. 44599; Sweden, January 7, 1920, Ser. No. 89/20; England, April 21, 1920, No. 142,116; Austria, February 18, 1920, Pat. No. 88,605; France, March 12, 1920, Pat. No. 511,496; Switzerland, February 10, 1920, Pat. No. 90,166), of which the following is a specification.

This invention relates to arrangements and connections of circuits, which are fed from a source of current having a pulsating voltage and in which the pulsations are substantially equalized in one or more work circuits in such a manner that the current in these circuits pulsates only slightly, constituting in the most favorable case a pure direct current. Such arrangements are necessary for instance in direct current circuits, which are fed from an alternating source of current by way of valve apparatus (vacuum rectifiers) because these devices, unless operated at a large number of phases, furnish pulsating direct current. The subject matter of the present invention is, however, independent of the manner of producing the pulsating direct current.

It is known that in supply circuits with pulsating voltage the pulsation of the current can be avoided by providing for the alternating current component of the pulsating continuous current a by-path or shunt with respect to the work circuit to be protected, which shunt is obtained by making the inductive resistance of this shunt circuit very small as compared with the inductive resistance of the work circuit to be protected. This may be effected by the insertion of self-induction in the work circuit and by the arrangement of ohmic resistances in the shunt circuit. However, these arrangements are effective only when the work circuits to which the shunt is connected, do not contain any voltage generators such as for instance, storage batteries, generators or motors, all of which generate independently E. M. F.'s i. e. electro-motive

forces, the directions and values of which are independent of the circuit supplying current to the work circuit.

In order to render the current uniform in circuits containing such individual, independent voltage generators, above mentioned, according to the invention, a shunt is formed for the alternating current component of the pulsating continuous current, by causing the alternating current component of the pulsating voltage to pass through a circuit connected in parallel with the consuming apparatus through the intermediary of a transformer, the said shunt circuit containing the secondary winding of the transformer. This secondary winding is connected in series with a continuous current generator, the voltage of which varies at the same rate as the voltage of the current consuming apparatus in the work circuit, this generator being adjusted so that only as much continuous current can flow through this circuit as is required for the maintenance of its working, for instance, for the driving the voltage generator or for the overcoming ohmic resistances.

Two arrangements for carrying the invention into effect are diagrammatically illustrated in Figures 1 and 2 of the accompanying drawings. It is assumed in both modifications, as an example, that the pulsating direct current is supplied through a vacuum valve, e. g. a mercury vapor rectifier 1. The anodes *a* of this rectifier are connected in known manner to the secondary winding of an alternating current transformer 2, which is connected to an alternating current supply circuit 3.

Referring more particularly to Figure 1, from the middle of the secondary transformer winding and from the cathode *c*, the conductors 4 and 5 respectively lead in the conventional manner to the work circuit, in which the current is to be rendered substantially uniform. This work circuit contains a direct current motor 6, having a shunt winding 7.

When the direct current motor 6 is in operation, an E. M. F. is generated at its brushes, whose value is variable independently of the E. M. F. in the supply circuit.

In order to prevent the alternating current pulsations from affecting this working

circuit, a transformer 12 is provided, whose winding 8 is located in the main circuit, and whose other winding 9 is arranged in parallel to the working circuit together with 5 auxiliary generator 13 which is in series with winding 9. Auxiliary generator 13 is driven by auxiliary motor 14 connected in parallel to motor 6, such that the field 15 of the auxiliary motor receives the full brush 10 voltage of motor 6, while its armature is controlled by starting resistance 16. 17 is the field of the auxiliary generator and is connected by way of field rheostat 18 in parallel to motor 6. It is the purpose of 15 this controllable auxiliary machine 13 to generate a direct current potential of the same direction as that of the utility motor 6, and variable in the same sense. Now if pulsating direct current flows through 20 transformer winding 8, its alternating current component is transferred into winding 9. Thus the current, due to this component is forced to flow through the branch circuit, containing winding 9 and 25 the auxiliary generator. In order to prevent a direct current of substantial intensity from flowing through this branch or shunt circuit, a counter E. M. F. is generated in auxiliary generator 13, which prevents the flowing of such direct current. On 30 the other hand, care should be taken that the self-induction of this auxiliary shunt circuit otherwise is small compared with that of the work circuit, so that in this 35 shunt circuit no substantial inductive resistance may oppose the alternating component of the pulsating current. It is therefore advisable to provide auxiliary generator 13 with compensating windings.

40 The object of the transformer winding 9 is to provide a shunt path for the alternating current part of the total current so as to relieve the work circuit of the alternating current component of the pulsating 45 current as much as possible. The winding 9 is so designed that the alternating current component, induced therein by transformation from the winding 8, compensates the component above referred to. The result 50 therefore is a continuous current rendered uniform in the work circuit without the superposition of an alternating current.

The resulting impedance of the transformer winding 9 is made smaller in itself 55 by co-acting with the second transformer winding 8 carrying the total pulsating current. In place of the impedance 9 an ohmic resistance may be used; the total impedance of the branch circuit can also be formed by 60 the auxiliary machine 13.

In the modification shown in Figure 2, a direct current shunt motor 13 serves for providing the counter electromotive force, which prevents the passing of the direct 65 current into the shunt circuit by which the

alternating current component is shunted around the work circuit. The shunt winding 17 of this motor is supplied with current from the work circuit branch which is free from pulsations. In this modification, a direct current flows in the shunt circuit only of a value, sufficient to run motor 13 at no-load. The speed of this motor always regulates itself automatically in such a manner that, disregarding the 70 drop in the no-load voltage, the counter E. M. F. appearing at its brushes always becomes equal to the continuous current voltage at the terminals of the work circuit. The impedances of the circuits can be adjusted by means of choking coils, for instance as shown at 19.

In Figure 2 a further modification according to the invention is shown, namely a direct current auxiliary winding 20 coupled with the transformer 12. This winding is fed from a direct current machine 21 driven from the shaft of the shunt motor 13 and the current is controlled by way of a regulator 22 and a choking coil 24. This 90 winding 20 has the purpose of neutralizing wholly or partially the direct current field of the transformer produced in the windings 8 and 9. A strong direct current field would impair the transformer in its character as an alternating current conveyor. The choking coil 24 is intended to smoothen out or suppress the alternating current component induced in the circuit of the winding 20 by the transformer alternating field. 100 In order to make the direct current intensity in the winding 20 dependent on the work current intensity, the machine 21 is provided with a compensating winding 23, in series with motor 6.

105 While the modifications shown and described contain dynamo electric machines in the shunt and work circuits, the arrangement, according to this invention, is also suitable for using any other kind of potential producers, such for instance as storage batteries or the like.

I claim:—

1. In a circuit arrangement of the character described, having a source of pulsating direct current and a work circuit containing a generator of potentials independent of that of the pulsating current, a circuit arranged in shunt to said work circuit and a transformer for causing the component alternating current of said pulsating current to pass through said shunt circuit, the primary winding of said transformer being located in the pulsating current supply circuit, the secondary winding being 115 located in said shunt circuit, and an independent auxiliary source of direct current potential located in said shunt circuit and means for controlling said source by the potential generator in said work circuit, to 120 125

vary the auxiliary potential in accordance with the potential in the work circuit.

2. In a circuit arrangement of the character described, having a source of pulsating direct current and a work circuit containing a generator of potentials independent of that of the pulsating current, a circuit arranged in shunt to said work circuit and a transformer for causing the component alternating current of said pulsating current to pass through said shunt circuit, the primary winding of said transformer being located in the pulsating current supply circuit, the secondary winding being located in said shunt circuit, and an independent auxiliary source of direct current potential located in said shunt circuit and means for controlling said source by the potential generator in said work circuit, to vary the auxiliary potential in accordance with the potential in the work circuit, and an impedance connected into said shunt circuit in series with said auxiliary potential source.

3. In a circuit arrangement of the character described, having a source of pulsating direct current and a work circuit containing a generator of potentials independent of that of the pulsating current, a circuit arranged in shunt to said work circuit and a transformer for causing the component alternating current of said pulsating current to pass through said shunt circuit, the primary winding of said transformer being located in the pulsating current supply circuit, the secondary winding being located in said shunt circuit, and an auxiliary direct current dynamo-electric machine located in said shunt circuit and having its field winding connected in parallel to the potential generator in said work circuit, to cause the variation of the auxiliary machine potential in accordance with that of the work circuit.

4. In a circuit arrangement of the character described, having a source of pulsating direct current and a work circuit containing a generator of potentials independent of that of the pulsating current, a circuit arranged in shunt to said work circuit and a transformer for causing the component alternating current of said pulsating current to pass through said shunt circuit, the primary winding of said transformer being located in the pulsating current supply circuit, the secondary winding being located in said shunt circuit, an auxiliary direct current dynamo-electric machine located in said shunt circuit and having its field winding connected in parallel to the potential generator in said work circuit, to cause the variation of the auxiliary machine potential in accordance with that of the work circuit, and demagnetizing means, controlled by the current in said work circuit for eliminating the direct current field in said transformer.

ent of that of the pulsating current, a circuit arranged in shunt to said work circuit and a transformer for causing the component alternating current of said pulsating current to pass through said shunt circuit, the primary winding of said transformer being located in the pulsating current supply circuit, the secondary winding being located in said shunt circuit, an auxiliary direct current dynamo-electric machine located in said shunt circuit and having its field winding connected in parallel to the potential generator in said work circuit, to cause the variation of the auxiliary machine potential in accordance with that of the work circuit, and demagnetizing means, controlled by the current in said work circuit for eliminating the direct current field in said transformer.

5. In a circuit arrangement of the character described, having a source of pulsating direct current and a work circuit containing a generator of potentials independent of that of the pulsating current, a circuit arranged in shunt to said work circuit and a transformer for causing the component alternating current of said pulsating current to pass through said shunt circuit, the primary winding of said transformer being located in the pulsating current supply circuit, the secondary winding being located in said shunt circuit, an auxiliary direct current dynamo-electric machine located in said shunt circuit and having its field winding connected in parallel to the potential generator in said work circuit, to cause the variation of the auxiliary machine potential in accordance with that of the work circuit, and demagnetizing means, controlled by the current in said work circuit for eliminating the direct current field in said transformer, said auxiliary machine and said demagnetizing means having choking coils connected in their respective circuits to smoothen out the alternating components in said shunt circuit.

In testimony whereof I affix my signature.
MORITZ SCHENKEL.
